UNITED STATES PATENT OFFICE.

WARREN BECKWITH, OF GENEVA LAKE, WISCONSIN.

WAGON END-GATE.

SPECIFICATION forming part of Letters Patent No. 286,675, dated October 16, 1883.

Application filed April 12, 1883. (No model.)

To all whom it may concern:

Be it known that I, WARREN BECKWITH, a citizen of the United States, residing at Geneva Lake, in the county of Walworth and State of Wisconsin, have invented certain new and useful Improvements in End-Gates, of which the following is a specification, to wit:

This invention relates to end-gates for vehicles; and it consists in the peculiar construction of the same, whereby it will be held firmly in position, and hold the sides of the wagon from spreading, and at the same time may be readily removed, substantially as will be hereinafter more fully set forth.

15 In order to enable others skilled in the art to which my invention appertains to make and use the same, I will now proceed to describe its construction and operation, referring to the accompanying drawings, in which—

20 Figure 1 is an end view, and Fig. 2 a plan view of a wagon-body having my end-gate attached.

A represents a wagon bed or body, upon the inner sides of which near the rear end are arranged the cleats or strips a a' between which the end-gate B is held. The strips a a' are formed with a groove, b, upon their outer sides, the purpose of which will be presently understood.

25 The strips a a' are secured to the sides of the wagon-body by hinges b', as shown, and may be turned backward so as not to project within the body, as shown by dotted lines in Fig. 2, and these strips are also provided with suitable handles, b², by which they may be moved.

The end-gate B is provided with one or more strips of metal along its edges upon the

inner side, which are bent at right angles to form a tongue, e, adapted to enter and slide 40 in the grooves b b of the cleats a a' , and thus prevent the sides from spreading. The outer side of the gate is also provided with two pivoted arms, B' B', adapted to be turned down against the hinged cleats a ' and prevent their 45 being moved.

It will thus be seen that when in position the gate is held firmly, and by its metal tongues e prevents the body from spreading, but may easily be removed, no matter what 50 the pressure of the load may be, by throwing up the arms B', and pulling out the hinged cleats a ', thus leaving the gate free to be removed without requiring force to remove it.

I am aware it is not new to provide an end-gate with hinged and grooved cleats; and I do not claim the same, broadly; but

What I do claim, and desire to secure by Letters Patent, is—

The combination of the wagon-body A, having cleats a a' , provided with grooves b b , and cleats a ' a' hinged to the sides of the wagon-body, and provided with handles b² b², the gate B provided with metal edge strips having right-angled tongues engaging with grooves 65 b b , and the locking-arms B' B' adapted to impinge against and lock the cleats a ' a' in a closed position, substantially as shown and described, and for the purpose set forth.

In testimony whereof I affix my signature in 70 presence of two witnesses.

WARREN BECKWITH.
